[57] CLAIM

The ornamental design for a radiator cooling fan, as shown.

DESCRIPTION

FIG. 1 is a front elevational view of a radiator cooling fan showing our new design;
FIG. 2 is a side elevational view thereof;
FIG. 3 is a rear elevational view thereof; and
FIG. 4 is a cross sectional view taken on line 4—4 of FIG. 3.

FIG. 1.

FIG. 2.

FIG. 3.

FIG. 4.
